UNITED STATES PATENT OFFICE.

EDWARD J. WHITE, OF CHESTER, PENNSYLVANIA.

FIRE-EXTINGUISHING MEANS.

Application filed September 19, 1922. Serial No. 589,183.

To all whom it may concern:

Be it known that I, EDWARD J. WHITE, a citizen of the United States, and a resident of Chester, in the county of Delaware and State of Pennsylvania, have invented certain new and useful Improvements in Fire-Extinguishing Means; and I do hereby declare the following to be a full, clear, and exact description of the invention, such as will enable others skilled in the art to which it appertains to make and use the same.

This invention relates to improvements in fire extinguishing means and particularly to such as are especially adaptable for use in extinguishing fire occurring in a moving picture apparatus,—one object of the invention being to provide simple and efficient means which shall be operated automatically to discharge chemical or other fire extinguishing fluid in the form of spray, on a burning section of film near the point of exit of the film from the upper reel receptacle or casing and also to automatically cause extinguishing fluid to be sprayed onto all exposed parts of the reeled film should the first spraying of the fluid fail to extinguish the fire of the burning film.

With this and other objects in view, the invention consists in certain novel features of construction and combinations of parts as hereinafter set forth and pointed out in the claims.

The accompanying drawing is a view, partly in section and partly in elevation, illustrating an embodiment of my invention.

In the drawing, I have shown at 1 the upper reel casing or receptacle of a moving picture machine, and a film reel mounted in said casing or receptacle is represented at 2. The film 3 passes from the reel through an opening 4 and between pairs of guide rollers 5. From the guide rollers 5, the film passes partly through a casing connection 6 and after passing between guide rollers 7—8 located in the casing connection, the film forms a loop 9 and then passes through the projecting apparatus indicated by dotted lines at 10.

Mounted upon the casing or receptacle 1 through the medium of brackets 12, is a reservoir 13 for suitable chemical fire-extinguishing fluid or material which is maintained under pressure from a suitable source of compressed air supply communicating with said reservoir through the medium of a valved connection indicated at 14.

A perforated spray pipe 15 is located within the casing 1 near the peripheral wall thereof and extends approximately from one side of the casing connection 6 to the other,— 60 said pipe being thus so disposed as to approximately encircle the film reel and the perforations in said pipe being so disposed as to direct spray of extinguishing fluid toward the centrally located film reel. A 65 short perforated spray pipe 16 projects partially across the casing connection 6 so as to be in position near the point in proximity to that portion of the film near the loop 6 where said film is most likely to become ignited from the effects of the electric lamp 70 of the apparatus.

The casing 17 of a valve 18 is connected with the longer spray pipe 15 (at an intermediate portion of the latter) and with the 75 fluid reservoir 13, and the stem of said valve is provided with an arm 19. A fuse cord 20 is secured at one end to the valve arm 19 and after extending through the casing 1 so as to pass in comparatively close proximity to the film reel, the other end of said fuse cord is secured to the short spray pipe 16, or to any other fixed part near the outlet of the casing 1. The fuse cord 20 normally retains the valve 18 closed against the action of a spring 21 which tends to open it, said spring being connected at one end with the valve arm 18 and at the other end to a lug 21^a on the reservoir 13.

The shorter spray pipe 16 is connected 90 with one end of a valve casing 22 and the other end of the latter is connected by a pipe 23 with the fluid tank 13. The valve 24 in the casing 22 is provided with an arm 25, to which one end of a fuse cord 95 26 is secured. This fuse cord extends partially through the casing connection so as to be disposed near portions of the film in proximity to the loop 9 and the projecting apparatus and the inner end of said fuse cord 26 is secured to a fixed part 27 located near the film guide rollers. The fuse cord 26 normally holds the valve 24 closed and a spring 28 attached at one end to the valve arm 25 and at the other end to a lug 29 on 100 casing 1, tends to open said valve.

Should the film become ignited near the projecting apparatus, the disruption of the fuse cord 26 would release the valve 24 and the spring 28 would act automatically to 110 open said valve and permit fluid from the reservoir 13 to be discharged from the spray

pipe 16 onto the burning film. This would in most cases be sufficient to extinguish the fire, but should the latter persist and follow the film to the reeled film, the fuse cord 20 5 would be disrupted or destroyed and the spring 21 would promptly open the valve 18, thus permitting fluid to enter the longer spray pipe 15 and to be sprayed on all exposed portions of the reeled film, thereby 10 quickly and effectually extinguishing all fire within the film reel casing and saving the major portion of the film.

Various changes might be made in the details of construction of my invention without departing from the spirit thereof or limiting its scope and hence I do not wish to restrict myself to the precise details herein set forth.

Having fully described my invention 20 what I claim as new and desire to secure by Letters-Patent, is:—

1. In devices of the character described, the combination with a film reel casing and a source of fire extinguishing material, of 25 a pipe having a perforated portion arranged to discharge in said casing in proximity to the outlet of said casing and provided with a portion communicating with said source of fire extinguishing material, a 30 valve between the ends of said pipe, a fuse near the path traveled by a film from said casing, said fuse holding said valve normally closed, and a spring tending to open said valve and operable automatically to 35 open said valve upon disruption of the fuse.

2. The combination with a film reel cas-

ing, of a spray pipe supported within said casing and adapted to approximately surround a film reel in said casing, a reservoir for fire-extinguishing material mounted upon said casing, a connection between said reservoir and spray pipe, a valve in said connection, a spring tending to open said valve, and a fuse extending into the casing and operable normally to hold said valve 45 closed.

3. In devices of the character described, the combination with a film reel casing having an outlet, and a reservoir for fire-extinguishing material, of a perforated spray 50 pipe located within said casing and adapted to approximately surround a film reel therein, a shorter perforated spray pipe located near the outlet of said casing, connections between said spray pipes and said reservoir, 55 valves in said connections, springs tending to open said valves, a fuse operatively connected at one end with one of said valves and secured at its other end within said casing, and a fuse operatively connected at one 60 end with the other valve and having its other end secured near the outlet of the casing, said fuses operable normally to retain said valves closed.

In testimony whereof, I have signed this 65 specification in the presence of two subscribing witnesses.

EDWARD J. WHITE.
